(57) **CLAIM**

The ornamental design for a display screen or portion thereof with a graphical user interface for analytics, as shown and described.

DESCRIPTION

FIG. 1 is a front view of a display screen or portion thereof with a graphical user interface for analytics showing a first embodiment of the new design; and,

FIG. 2 is a front view of display screen or portion thereof with a graphical user interface for analytics showing a second embodiment.

Within the drawings, the broken lines show the display screen or portion thereof and the portions of the graphical user interface which are excluded from the claim and form no part of the claimed design.

1 Claim, 2 Drawing Sheets
